(57) **CLAIM**

The ornamental design for a tape measure with laser module, as shown and described.

DESCRIPTION

FIG. 1 is a perspective view of a tape measure with laser module according to the present invention;

FIG. 2 is an elevated front view of the tape measure with laser module of FIG. 1;

FIG. 3 is an elevated rear view of the tape measure with laser module of FIG. 1;

FIG. 4 is a right side view of the tape measure with laser module of FIG. 1;

FIG. 5 is a left side view of the tape measure with laser module of FIG. 1;

FIG. 6 is a top view of the tape measure with laser module of FIG. 1;

FIG. 7 is a bottom view of the tape measure with laser module of FIG. 1; and,

FIG. 8 is a perspective view of the tape measure with laser module of FIG. 1, with the side slide panels in an alternative position.
